UNITED STATES PATENT OFFICE.

JOHN F. O'NEIL, OF ST. LOUIS, MISSOURI, ASSIGNOR TO FULTON IRON WORKS COMPANY,
OF ST. LOUIS, MISSOURI, A CORPORATION OF DELAWARE.

CANE-MILL.

1,291,095.

Specification of Letters Patent. Patented Jan. 14, 1919.

Application filed January 13, 1917. Serial No. 142,204.

To all whom it may concern:

Be it known that I, JOHN F. O'NEIL, a citizen of the United States of America, a resident of the city of St. Louis, State of Missouri, have invented certain new and useful Improvements in Cane-Mills, of which the following is a full, clear, and exact description, reference being had to the accompanying drawing, forming a part of this specification.

My invention relates to a cane mill, and it has for its object to provide precrushing means whereby the capacity, juice extraction, and percentage of sugar yield from the cane of a cane mill may be greatly increased relative to the capacity of such mills as have heretofore been in use.

Figure I is a longitudinal section through part of a cane mill including a set of mill rolls and my improved precrushing means.

Fig. II is an enlarged longitudinal section of fragments of the primary precrushing rolls, illustrating the intermeshing teeth of these rolls.

Fig. III is a view similar to Fig. II of the secondary precrushing rolls, illustrating the intermeshing teeth of said secondary rolls.

In the drawings, A designates a set of juice expressing rolls in triangular arrangement, as is customary in cane mills. Any desired number of such sets of rolls may be used in series following that shown through which the cane may pass after it has been precrushed by passage through my precrushing means.

1 and 2 designate roll housings located in front of the rolls A, the housing 2 being located nearest the said rolls A and having its journal boxes at a less elevation than the 40 journal boxes in the housing 1. The two housings 1 and 2 are so mounted on suitable supports as to incline forwardly.

The primary housing 1 supports a set of primary grooved precrushing rolls 3 between which the cane to be treated first passes as it rides down an inclined runway 4 leading to said rolls 3.

5 designates secondary precrushing rolls arranged tandem with the primary rolls 3 and more closely assembled than the latter. Between the rolls 3 and 5 is an inclined runway 6 onto which the partially crushed cane passes as it emerges from between the primary precrushing rolls 3, said runway

serving to conduct the cane to the secondary precrushing rolls 5.

The teeth 5^a of the secondary precrushing rolls (Fig. III) are smaller than the teeth 3^a of the primary precrushing rolls (Fig. II), and they, therefore, are capable of performing a more complete crushing and shredding action than that which is performed by the teeth of the primary precrushing rolls.

7 designates an inclined runway leading from the secondary precrushing rolls 5 to the mill rolls A.

In the practical use of my cane mill, the cane to be crushed is delivered to the inclined runway 4 and descends by gravity thereon to the primary precrushing rolls 3.

These rolls are separated from each other a sufficient distance to permit of the continuous passage of a large quantity of cane between them with resultant initial crushing of the cane, and sufficient compression and condensation of the mass of cane to permit of such mass passing readily between the secondary precrushing rolls when such mass has descended the inclined runway 6 between the sets of rolls. It will be obvious that the secondary set of precrushing rolls will readily receive and crush the same quantity of cane as has passed between the more widely separated rolls of the primary or first set, even though the former are more closely assembled, this fact being due to the initial partial crushing and condensation of the cane mass. The secondary set of precrushing rolls preferably has smaller and more closely associated teeth which act not only to further compress the cane, but also to shred it and put it in a condition which makes it possible for the mill rolls A, and similar sets of rolls succeeding said set, to extract the juice from the cane as rapidly as it is delivered thereto, notwithstanding the fact that the degree of delivery is far in excess of the degree of delivery in the ordinary cane mill.

The two sets of toothed precrushing rolls results, as the mass of cane passes through the second set of said rolls, in giving to said mass a rolling or twisting motion whereby the splitting and shredding of said mass is facilitated and better prepared for the subsequent operations by the juice expressing rolls.

In consequence of the second set of pre-crushing rolls being differentiated from each other, as the cane passes through the second set of rolls while it is still held between the rolls of the first set an action takes place which tends constantly to place the cane under strain while it is being shredded by the teeth of the several precrushing rolls. The cane is, therefore, so operated upon as to cause its cells to be thoroughly opened up in order that practically all of the juices therein may be driven from the cells by the juice expressing rolls of the cane mill.

I claim:

1. The combination with juice expressing rolls of a cane mill, of a plurality of sets of toothed precrushing rolls through which the cane is passed before delivery to the juice expressing rolls, said sets of precrushing rolls being operable in a differentiating degree upon the cane to shred and open its

cells before the cane reaches the juice expressing rolls.

2. The combination with juice expressing rolls of a cane mill, of two sets of toothed precrushing rolls arranged to receive the cane in advance of said juice expressing rolls, the teeth of the precrushing rolls nearest said juice expressing rolls being arranged to effect a twisting action upon the cane as it passes through said rolls.

3. The combination with juice expressing rolls of a cane mill, of two sets of toothed precrushing rolls in rear of said juice expressing rolls, the teeth of the precrushing rolls nearest said juice expressing rolls being smaller than the teeth of the other precrushing rolls.

In testimony that I claim the foregoing I hereunto affix my signature.

JOHN F. O'NEIL.
